UNITED STATES PATENT OFFICE.

WILLIAM H. PLATT, OF HAMILTON, OHIO.

JAR HOLDER.

Application filed March 27, 1923. Serial No. 627,976.

To all whom it may concern:

Be it known that I, WILLIAM H. PLATT, a citizen of the United States, residing at Hamilton, in the county of Butler and State of Ohio, have invented certain new and useful Improvements in Jar Holders, of which the following is a specification.

In carrying out the present invention, it is my purpose to provide a highly improved form of means of holding jars and the like in the removal or application of the lid from or to jars, the device being characterized by its simplicity of construction, comparative inexpensiveness of manufacture, and ease of operation.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:—

Figure 1 is a top plan view of my improved jar holder.

Figure 2 is a side elevation thereof.

Figure 3 is a perspective of one of the jar holding members, and

Figure 4 is a similar view of a rubber strip carried by the said jar.

Referring to the drawings in detail, 5 designates a base plate, wherein the front ends of the side edges thereof are converged inwardly, and formed at their terminal point with a vertically projecting knob or head 6. Upon opposite sides of the said base plate and substantially intermediate the ends thereof, are raised projections 7 of slightly arcuate shape, the front end of this plate being further provided with an inwardly extending hook element 8, with which is associated a wellknown type of clamp member 9, for permitting said base plate to be rigidly secured upon the edge of a table or other suitable support.

Loosely, pivotally secured to the said head or knob 6 are inwardly curved ends 10 of substantially J-shaped arms 11. Resting upon the said projections 7 upon opposite

sides of the base plate 5 are arcuate shaped jaws 12, the outer edge of each being formed with laterally projecting lip or ear 13, pivotally secured at 14 to its complementary arm 11. As more clearly shown in Figure 3, each of these jaws are channeled upon their inner edge at 15, for receiving an arcuate-shaped rubber strip 16, Figure 4, for obvious purposes.

Pivoted upon the free end of one of the jaws 10 is a cross link 17, this pivoted end of the link being provided with a plurality of openings 18, for the reception of the pivot 19, whereby adjustment may be procured between the arms 11 and consequently the jaws 12. The opposite end of this link 17 is pivoted at 20 adjacent one end of a lever 21, the end of this lever adjacent said pivot being in turn pivoted at 22 to the opposite arm 11, whereby when a jar is positioned upon the said base plate 5, the lever is swung to the position shown in Figure 1, for consequently extending the jaws inwardly for effectively grasping and maintaining rigidly a jar or similar article.

In view of the above description, it is believed by me that it will be at once apparent to those skilled in the art, that I have provided a highly improved jar holder, and one that will embrace the desired features of simplicity, durability and efficiency, and although I have herein shown and described the preferred embodiment of the invention, it is nevertheless to be understood that minor changes may be made therein, without departing from the spirit and scope of the invention as claimed.

Having thus described my invention, what I claim as new, and desire to secure by Letters-Patent, is:—

1. In a jar holder, a base plate, means for securing said base plate upon a support, a pair of substantially J-shaped arms pivoted at their curved ends to one end of said plate, jaws carried by said arms, and means for swinging said arms upon the pivot for consequently opening or closing said jaws.

2. In a jar holder, a base plate, means for securing said base plate upon a support, a pair of substantially J-shaped arms pivoted at their curved ends to one end of said base plate, jaws carried by said arms, means for

swinging said arms upon the pivot for consequently opening or closing said jaws, and said jaws being formed with channels upon their inner sides, and rubber strips within said channels, and projecting outwardly therefrom.

3. In a jar holder, a base plate, a pair of arms pivoted at one end to one end of said

base plate, jar members pivoted substantially intermediate the ends of said arms and 10 engaging over the sides of said plate, means for supporting said jaws above said plate and means for expanding and contracting said jaws.

In testimony whereof I affix my signature.
WILLIAM H. PLATT.
